UNITED STATES PATENT OFFICE

HENRY FORD, OF DEARBORN, MICHIGAN, ASSIGNOR TO FORD MOTOR COMPANY, OF DEARBORN, MICHIGAN, A CORPORATION OF DELAWARE

GRINDING MACHINE

Application filed May 28, 1929. Serial No. 366,680.

The object of my invention is to provide a grinding machine of simple, durable and inexpensive construction.

Still a further object of my invention is to provide a grinding machine which will automatically grind the bore in a split type valve bushing. These valve bushings consist of a pair of semi-circular halves so formed that when placed together a bushing very similar to the solid valve bushing ordinarily used in motor car engines is produced.

Many advantages are gained when these bushings are used in an engine, the principal advantage being that each half of the bushing may be die cast separately and allowed to chill in the mold thereby forming an extremely hard valve stem bearing surface for the bushing. The meeting flat faces are then ground on an ordinary surface grinder after which the outer diameter of a pair of bushings is ground round. The semi-circular bearing surfaces in which the valve stem reciprocates are then ground with a large form wheel, the cutting edge of which has previously been dressed to the radius of the valve stem.

It may be readily seen that if these bushings were made solid instead of in halves, the bore in the bushing would have to be drilled or ground with a wheel of a smaller diameter than the valve stem. Drilling chilled bushings is, of course, impossible; while grinding the bore with an extremely small wheel is not commercially successful. With this so called split bushing, the applicant uses a large form wheel to grind the valve stem bearing surface, and the grinding machine which is the subject of this application performs this grinding operation.

Each of these half bushings must be an exact duplicate of each other, the bearing surfaces must be an exact semi-circle having a fixed radius and the outer circumference must be concentric with the bore so that any two half bushings which may be picked at random will produce a perfect bushing.

Still a further object of my invention is to provide a grinding machine in which the work to be ground is rotated around a fixed center to position adjacent to a series of revolving grinding wheels, and to vary the

radial position of the work as it rotates so that the line of contact of the work with the revolving grinding wheels is tangent to the wheels.

In most progressive machine operations the piece to be machined is passed from one machine to the next on a conveyor or some similar device, the piece being clamped to the conveyor or reclamped in fixed dies on each machine. Due to the extreme accuracy required in this particular part, it has been found impractical to use any type of conveyor or the like for advancing the work from one grinding wheel to the next as the location of the work in reference to each succeeding grinding wheel cannot be held accurately enough. If the work is successively clamped in a series of dies held in fixed position in relation to the grinding wheels the variation obtained when clamping the work in the various dies produces variations in the finished dimensions of the piece.

In the majority of grinding operations in which great accuracy is obtained the work is rotated around a center and the grinding wheel moved against the work thereby grinding a very accurate circumference. Only arcuate surfaces may be ground by this method because regardless of how large the radius of grinding is made an arc will be formed and not a flat surface.

In the applicant's machine the work is rotated around a fixed center and the distance of the work from the fixed center is varied as the work revolves, so that the successive points of contact of the work with the grinding wheel results in a straight line. The accuracy obtained with the circular grinding process is thus obtained together with the advantage that flat work may be ground thereon.

With a very minor change in the applicant's machine, surfaces may be ground to a desired irregular contour. These irregular surfaces are very difficult to grind to accurate dimensions by any other method known to the applicant. Although the grinding of a piece having a flat surface is more fully described in the specification, any irregular or

arcuate surface may be just as readily ground in the machine.

Still a further object of my invention is to provide a novel means for rotating the work holder very slowly while the work is being ground and rapidly between the grinding operations. Various designs of elliptical gears have been used to vary the velocity of two shafts, but the limit of variation obtainable with these gears together with the fact that smooth grinding work cannot be accomplished where this type of gearing is used has made it imperative that a variable motion device having a wide range and smoother operating characteristics be devised. The applicant's structure is very simple and produces a very steady acceleration and deceleration of the work holder.

Still a further object of my invention is to provide a grinding machine in which the work is resiliently held in a work holder and to provide means so that when the work holder is rotated through one revolution the work will be automatically discharged from the machine. It is only necessary in the applicant's machine to place the bushing into the work holder, they being automatically conveyed to each of the three grinding wheels and then automatically discharged from the machine.

With these and other objects in view my invention consists in the arrangement, construction and combination of the various parts of my improved device, as described in the specification, claimed in the claims, and illustrated in the accompanying drawings, in which:

Figure 1 shows a vertical central sectional view through the main spindle of the machine.

Figure 2 shows a sectional view taken on the line 2—2 of Figure 1.

Figure 3 shows a diagrammatic view of the work holders, grinding wheels, and stationary cam, to illustrate the sequence of the grinding operations and the method used to develop a flat grinding surface.

Figure 4 shows a plan view of one of the work holder assemblies.

Figure 5 shows a sectional view taken on the line 5—5 of Figure 4.

Figure 6 shows an enlarged sectional view taken on the line 6—6 of Figure 5, and

Figure 7 shows a sectional view of the inner side of the work holder on the line 7—7 of Figure 1.

Referring to the accompanying drawings I have used the reference numeral 10 to indicate generally the base of the machine. This base 10 consists of a rectangular box shaped structure having a flat machined upper surface 11 to which the various parts of the machine are secured. A rim 12 is secured to the plate 11 and extends around its outer edge 65 to form a pan or trough for collecting the

cooling fluid used with the machine. The base member 10 is internally braced to give great rigidity to the parts mounted thereon to thereby secure very accurate work with the machine.

A bracket 13 is secured on one end of the base plate 10 and extends vertically therefrom. The center portion of this bracket is provided with a bearing 14 for the main spindle of the machine. In this machine three grinding wheels are rotated by means of electric motors and the work to be ground is passed successively underneath each of these wheels. Each of the electric motors 15 are secured to a slide 16 which is mounted for radial movement in the bracket 13. The slides themselves have not been shown in detail as they are of ordinary structure and form no part of the invention except as a means for adjustably mounting the grinding wheels.

The motors 15 extend forwardly from the slides 16 and guard members 17 are secured to the opposite side of the slides and partially enclose the grinding wheels used on the machine. The grinding wheels, motors and slides are of the conventional direct connected type used for ordinary grinding.

Three grinding wheels are provided, as shown in the diagrammatic view in Figure 3. The first and second wheels 18 are roughing wheels, while the third wheel 19 is a finishing wheel. As the grinding wheels wear down the slides 16 are moved inwardly to compensate for the wear of the wheel so that the travel of the work to be ground can be a fixed path, irrespective of the wear on the wheels.

The opposite end of the base plate 10 is provided with a housing 21 which is secured to this plate by means of an integral flange 22. A bearing 23 is formed in the outer end of housing 21 and is aligned with the bearing 14 in the bracket 13.

A spindle 24 is rotatably mounted on the bearings 14 and 23 and a cap 25 is secured to the outer end of the bearing 14 to absorb the end thrust produced by the spindle 24. A second cap 26 is secured over the outer end of the bearing 23 to enclose the spindle 24. A thrust screw 27 is secured in the spindle 24 adjacent to the cap 26 and a thrust plate 28 is resiliently mounted in the cap 26 by means of the springs 29 so that the spindle 24 may be resiliently urged against the thrust plate 25 by the springs 29.

A drum shaped member 30 is formed integral with the spindle 24 adjacent to the inner end of bearing 14 and extends radially therefrom. A plurality of bearings 31 are provided in the periphery of the drum 30 parallel to the spindle 24 and a work holder assembly is rotatably mounted in each of these bearings 31. In the form of machine here shown, eight work holders are provided equally spaced around the drum 30. When

the spindle 24 rotates in the bearings 14 and 23 the drum 30 and work holders also rotate.

Referring to Figure 4, a sleeve 32 is rotatably mounted in each bearing 31, the outer end of each sleeve having an arm 33 extending along the periphery of the drum 30. A block 34 is formed integral with the outer end of the arm 33 and is of rectangular shape and has an outwardly opening longitudinal slot 35 formed therein. A pair of plates 36 partially enclose the slot 35 and are secured to the block 34 by means of the screws 37. A space, slightly wider than the thickness of the grinding wheels 18 or 19 is allowed between the two plates 36 so that there is ample clearance for these wheels to operate between the two plates.

The inner end of each sleeve 32 is secured to a second arm 38 by means of the screws 39 and extends substantially parallel to the arm 33. A roller 40 is pivotally mounted between the ears 42 on the outer end of the arm 38 by means of a pin 41.

The construction just referred to consists briefly of a sleeve having a pair of arms extending from each side thereof, one of the arms being provided with a roller at its outer end and the other arm with a block so that movement of the roller will cause a like movement of the block.

A shaft 43 is extended through the sleeve 32 and an arm 44 is formed integral with the outer end of the shaft and extends substantially parallel to the arm 38. The outer end 35 of the arm 44 extends into the slot 35 in the block 34 and a shoe 46 is pivotally secured to this arm within the slot 35 by means of a pin 47. The outer face of the shoe 46 is provided with a V-shaped groove so that the bushing to be ground, shown by the dotted lines 48, may be clamped between this V shaped groove in the shoe and the plates 36. There is a considerable movement of the shoe 46 within the slot 35 so that when the arm 44 is rotated clockwise, referring to Figure 5, the shoe 46 will clamp the bushing 48 against the plates 36.

A lever 45 is fastened to the inner end of the shaft 43 by means of the studs 49 and extends in the general direction of the arm 38. A leaf spring 61 is secured to the lever 45 adjacent to its hub also by means of the studs 49 and the outer end of this spring bears against an adjustable stop secured to the lever 38. When the spring 61 is installed it is flexed to such position that the shaft 43 and arm 44 will resiliently force the shoe 46 against the plates 36. An eccentric sleeve 50 is rotatably mounted on a stud 62 extending from the arm 38 beneath the spring 61. Suitable slots 51 are provided in the periphery of the eccentric 50 for rotating same for adjustment. A nut is arranged to lock the eccentric 50 in any desired position around the stud 62.

It may thus be seen that rotating the eccentric 50 will vary the spring pressure of the leaf spring 61 thereby varying the pressure of the shoe 46 against the bushing 48. The operator of the machine is thus able to resiliently clamp the bushing 48 between the shoe 46 and the plates 36 with a wide range of adjustable spring pressures.

When it is desired to release the bushing 48 from between the plates 36 and shoe 46, the outer end of the lever 45 is moved inwardly thereby rotating the shaft 43 against the resilient pressure of the spring 61 to thereby lower the shoe 46 from the bushing. This same operation is repeated when it is desired to insert a new bushing in the block 34.

It will be noticed that the sleeve 32, shaft 43, arms 33, 38, and 44, together with the lever 45 and spring 61, oscillate as a unit in the bearing 31 during all of the grinding operations. The bushing 48 is clamped at the beginning of a revolution of the drum 30 and is not released until it has passed beneath the three different grinding wheels of the machine.

A cover plate 53 is secured to the inner end of the housing 21 and an extension 54 is formed integral with this cover plate 53 and extends between the cover plate and the drum 30. This extension 54 forms an enclosure between the drum 30 and the plate 53 thereby providing a dust free compartment for the inner ends of the work holding mechanism.

The cover plate 53 is provided with an opening 55 so that the spindle 24 may extend therethrough. A cam 52 is secured to the plate 53 adjacent to the opening 55 in such position that when the drum 30 is rotated the rollers 40 will follow the contour 105 of this cam 52 to thereby oscillate the sleeves 32 in the bearings 31.

Three substantially flat portions 56 are provided on the cam 52 so that the rollers 40 will operate against these flat portions when the bushings 48 are being ground by the grinding wheels. It may be well to mention here that due to the arcuate travel of the sleeve 32, the cam surface 56 is not exactly flat but is of such a contour that a straight surface 115 will be ground by the wheels 17 and 18 in the bushings 48. In the building of the machine, the cam 52 is machined to approximate size and then mounted on the cover 53. A solid steel wheel is clamped in place of the 120 grinding wheels 18 and 19 and a finished bushing is placed in the work holder. A portable grinding wheel is rotatably mounted on the clevis on the end of the arm 38 in place of the roller 40 and the shaft 24 is then rotated. The bushing 48 is held up against the flat surface of the aforementioned steel roller and the slight radius is ground on the cam 52 by means of the grinding wheel used 125 in place of the roller 40.

If an irregular surface is desired to be ground, a template or finished piece is inserted instead of the bushing 48 and the cam 56 is finished from this template. When the machine is normally operated the ground surface will be identical with the template used to grind the cam 56.

The normal operation of the device is just the reverse of the method used to grind the cam, that is, the roller 40 operates against the contour of the cam 56 to produce a corresponding ground surface on the piece to be ground.

A pin 57 extends inwardly from the arm 38 and one end of a coil spring 58 is hooked over this pin and the other end secured to the spindle 24 so that the roller 40 may be resiliently urged against the cam 52 by means of this spring.

20 A trip block 59 is mounted in the interior of the extension 54 and projects inwardly so that the outer end of the lever 45 will be forced inwardly as it passes this trip block. The bushing 48 which is clamped in the work holder at this time is thereby released and drops to the bottom of the machine.

25 A second trip block 60 is secured to the plate 11 in the path of the outer ends of the levers 45, so that as each lever advances over this trip block a new bushing may be placed in the work holder by the operator of the machine. When the drum 30 advances so that the outer end of a lever 45 slides over the trip block 60, the spring 61 clamps the bushing 48 between the shoe 46 and the plates 36.

30 Means have been provided for increasing the speed of the spindle 24 when the bushings 48 are travelling between the grinding wheels. If a constant rotation of the shaft 24 were provided, only a very small percentage of the time required for one rotation of each shaft would be utilized in grinding the bushings, and as the grinding operation is such that an appreciable amount of time must be taken for grinding each bearing, a great saving of time is obtained if the spindle 24 is speeded up between the grinding operations.

35 A sleeve 63 is rotatably mounted on the spindle 24 adjacent to the bearing 23 and the worm wheel 64 is secured to this sleeve by means of a radial flange 65 formed integrally with the sleeve 63. A gear 66 is machined in the opposite end of the sleeve 63. A worm 67 is mounted in the lower part of the housing 21 transversely to the spindle 24 in position to mesh with the worm wheel 64. Suitable bearings 68 are provided for this worm and an electric motor 69 is connected thereto through an extension shaft, not shown in the drawings. The rotation of the motor 69 thereby rotates the worm 67 which operates with the worm wheel 64 to rotate the sleeve 63 and gear 66.

40 An arm 70 is rotatably mounted on the spindle 24 adjacent to the sleeve 63 and ex-

tends downwardly to a position near the base plate 10. A bearing 71 is provided in the lower end of the arm 70 parallel with the spindle 24 and a shaft 72 is rotatably mounted in this bearing. A gear wheel 73 is secured to the rear end of the shaft 72 by means of keys 74 and a cap screw 75 and washer 90.

45 An eccentric 76 is secured to the shaft 72 adjacent to the forward end of the bearing 71 and a pinion 77 is formed integral with the forward end of this shaft adjacent to the eccentric 76. The gear 73, shaft 72, eccentric 76, and pinion 77 are for all purposes a unit and rotate together at all times. A bull gear 78 is secured to the spindle 24 by means of keys 79 and a nut 80 in position to mesh with the pinion 77.

50 A link 81 is pivotally secured to one wall of the housing 21 by means of a pin 82 and clevis 83, the latter being formed integrally with the housing 21. A large split bearing 84 is formed on the opposite end of this link which is journalled on the eccentric 76. This bearing is provided with the conventional bearing cap 85 which is secured thereto by means of the screws 86.

55 When the shaft 72 is rotated, the eccentric 76 rotates with it and oscillates the link 81 around the pin 82, the link being free to oscillate in an arcuate path around the pivot pin 82. The shaft 72 being mounted in the bearing 71 of the arm 70 which is rotatably mounted on the spindle 24, is not free to oscillate in this arcuate plane but is only free to oscillate in an arcuate plane having the spindle 24 as a center. It will thus be seen that when the shaft 72 is rotated an oscillating movement will be imparted to the link and arm 81 and 70 around the pivot pin 82 and spindle 24, respectively, the link 81 compensating for the vertical movement of the eccentric and the arm 70 compensating the lateral movement of this eccentric.

60 To operate the device, the motor 69 is started which rotates the worm 67, worm wheel 64, and gear 66. The gear 66 being in mesh with the gear 66 thereby rotates the shaft 72, eccentric 76, and pinion 77 in a counterclockwise direction, referring to Figure 2. As has been previously explained, the rotation of the eccentric 76 oscillates the arm 70 and shaft 72 around the spindle 24 and, as the pinion 77 is formed integral with the shaft 72 the bull gear 78 would also be oscillated if it were not for the rotary movement imparted thereto by the pinion 77. This gear 78 will thereby rotate in a clockwise direction, looking from the forward end of the machine, an amount equal to the pitch line of travel of the pinion 77 plus the movement of the shaft 72 around the center of the spindle 24. This results in a fast movement of the gear 78 and spindle 24.

65 This aforementioned movement occurs during one half of the revolution of the shaft 130

72. When the shaft 72 completes the revolution, the movement of the bull gear 78 is the result of the difference between the counter-clockwise movement of the pinion 77 minus the movement of the arm 70 in the opposite direction. This results in a slow movement of the spindle 24.

The ratio of the pinion 77 to the bull gear 78 is as one is to eight so that there will be 70 eight variable speed cycles of the bull gear 77 for each revolution thereof. As there are eight work holders on the drum 30, each cycle advances the drum the distance between each work holder. The parts of the device are so 75 timed that during the slow movement of the drum 30 the bushings 48 in the work holders 34 will be passing beneath the grinding wheels 18 and 19.

Any desired grinding speed can be obtained 20 for the bushings 48 by varying the throw of the eccentric 76 relative to the pitch circle of the pinion 77. In this device one half of the operating cycle of the machine is used to move the bushings between the grinding 25 wheels while the rest of the cycle is used for the actual grinding operation on the bushing. A much greater production is obtained by the use of this structure over a machine in which a constant velocity is given 30 to the drum 30.

The lubrication of the device is accomplished 25 by providing a pocket 87 in the base plate 10 adjacent to the gear 73 which may be filled with oil so that when the gear 73 rotates through this pocket the gear teeth 30 will be lubricated. A second pocket 88 is also provided in the base plate 10 adjacent to the eccentric 76 and is also filled with oil so that this eccentric may be likewise lubricated. A third pocket 89 is provided in the 35 housing 21 adjacent to the worm 67 and is also filled with lubricant to lubricate the worm 67 and worm wheel 64. Suitable oil cups and fittings are provided for the other 40 bearings of the machine but are not shown in the drawings because of their conventional nature.

Many advantages arise through the use of 45 my improved grinding machine and it may be well to point out that with this machine a flat straight trough may be ground in a piece of work which is attached to a rotating work holder thereby insuring great accuracy in the ground surface. The work is not 50 clamped between any of the grinding operations which adds materially to the accuracy obtained.

Further, a novel means is provided for 55 varying the speed of rotation of the work holders, and one which produces a very steady acceleration and deceleration of this work holder.

Some changes may be made in the construction, arrangement, and combination of 60 the various parts of my improved device

without departing from the spirit of my invention and it is my intention to cover by my claims such changes as may reasonably be included within the scope thereof.

I claim as my invention:

1. In a grinding machine, a drum rotatably mounted therein having a plurality of shafts rotatably mounted around the periphery thereof, a stationary cam member, a plurality of grinding wheels mounted on said machine, an arm extending from one end of each of said shafts having a roller rotatably mounted thereon in position to co-act with the cam, a second arm extending from the opposite end of each of said shafts in position 80 adjacent to said grinding wheels, and a work holder secured to the outer end of each second mentioned arm, the parts being so arranged that as the drum revolves a portion of the path of the work holders will be tangent to each of said grinding wheels.

2. In a grinding machine having a drum rotatably mounted, a sleeve mounted in said drum parallel to its axis, a driven grinding wheel, a stationary cam member, an arm extending from one end of said sleeve to position adjacent to the grinding wheel and having a work holder formed on its outer end, a second arm extending from the opposite end of said sleeve to a position adjacent to 90 the cam, a shaft extending through said sleeve, a third arm secured to said shaft and extending to position to co-act with said work holder, and a spring secured to the opposite end of said shaft and co-acting with said second mentioned arm to resiliently urge the third mentioned arm into engagement with said work holder.

3. In a grinding machine, a drum rotatably mounted, a plurality of driven grinding 105 wheels mounted around said drum, a plurality of sleeves mounted for oscillation in the drum near its periphery, a stationary cam member, an arm extending from one end of each sleeve and having a work holder formed on its outer end, a second arm extending from the opposite end of said sleeve 110 adjacent to the cam and having a roller pivotally mounted therein, a shaft extending through said sleeve, an arm secured to the said shaft and extending into the work holder and adapted to clamp the work to be ground in said work holder, a leaf spring secured to the opposite end of said shaft, and an eccentric bushing rotatably mounted on the said second mentioned arm in position to co-act with said leaf spring for varying the clamping pressure between the third mentioned arm and the work holder.

4. In a grinding machine, a spindle rotatably mounted, a work holder supported by said spindle, a grinding wheel in position so that when said spindle is rotated the work holder will travel adjacent thereto, an arm rotatably mounted on said spindle, a shaft 125

rotatably mounted in said arm parallel to said spindle, means for driving said spindle through said shaft, and means for oscillating said arm to vary the rotating speed of said spindle.

5. In a grinding machine, a spindle rotatably mounted and having a drum secured to one end thereof, a plurality of grinding wheels mounted on said machine, a plurality of work holders mounted near the periphery of said drum in position so that when the drum is rotated the work holders will pass adjacent to the faces of the grinding wheels, a driving gear rotatably mounted on said spindle, an arm rotatably mounted on said spindle, a driven gear secured to said spindle, a shaft rotatably mounted in said arm parallel to said spindle, a gear secured to one end of said shaft and in mesh with said driving gear, a pinion secured to the opposite end of said shaft and in mesh with the driven gear, an eccentric secured to said shaft, and an eccentric arm rotatably mounted on said eccentric and pivotally mounted in said machine, the parts being so arranged that a uniform motion of said driving gear will produce a non-uniform motion of said driven gear.

6. In a grinding machine, a plurality of grinding wheels mounted in said machine, a spindle rotatably mounted in said machine, a plurality of work holders carried by said spindle, means for moving the work holders tangent to said grinding wheels over a portion of a revolution of the spindle, and means for varying the speed of rotation of said spindle so that the said work holders will travel substantially slower over the tangential path than over other portions of their travel.

40 7. In a grinding machine, a plurality of driven grinding wheels, a spindle rotatably mounted in said machine and having a drum secured thereto, a plurality of work holders mounted on said drum and arranged for tangential movement relative to said grinding wheels, a driving gear rotatably mounted on said spindle, a driven gear secured to said spindle, an arm rotatably mounted on said spindle between said mentioned gears, a shaft rotatably mounted in said arm, and gears on each end of said shaft in mesh with said first mentioned gears respectively, an eccentric secured to said shaft having an eccentric arm pivotally mounted in said machine, and means for driving said driving gear.

8. In a machine of the character described, a frame, a tool rotatably mounted on said frame, a drum rotatably mounted on said frame, a work holder pivotally mounted on a fixed axis in said drum, means for clamping an article in said work holder, the surface of said article to be machined being spaced from said axis, and means for oscillating said work holder as the drum revolves so that a non-

circular path is described by the surface to be machined.

9. In a machine of the character described, a frame, a tool rotatably mounted on said frame, a drum rotatably mounted on said frame, a work holder pivotally mounted on a fixed axis in said drum, means for clamping an article in said work holder, the surface of said article to be machined being spaced from said axis, and a stationary cam around which said work holder revolves adapted to oscillate said work holder so that a non-circular path is described by the surface to be machined.

10. In a machine of the character described, a frame having a tool rotatably mounted therein, a drum rotatably mounted in said frame, a work holder rotatably mounted on a fixed axis in said drum and means for oscillating said work holder as the drum revolves so that the resultant path of the work holder will be tangent to the rotating tool.

11. In a machine of the character described, a frame having a grinding wheel rotatably mounted therein, a drum rotatably mounted in said frame, a plurality of work holders mounted to rotate on fixed axes in said drum, and means for oscillating said work holders as the drum revolves so that the resultant paths of the work holders will be tangent to the grinding wheel.

May 20, 1929.

HENRY FORD.
